UNITED STATES PATENT OFFICE

2,066,132

STUB PULLER AND METHOD OF FORMING
THE SAME

Leon L. Zihler, Buffalo, N. Y.

Application November 5, 1935, Serial No. 48,360

2 Claims. (Cl. 76—101)

This invention relates to a stub extractor and method of forming the same and more particularly to an improvement on the form of stub extractor described in my United States Patent No. 5 1,108,059, dated August 18, 1914.

The stub extractor forming the subject of the present invention is primarily designed for the removal of broken ends of pipe or other objects which are open in the center or which can be 10 open in the center to permit of the insertion of the extractor. With pipe fittings it frequently happens that a pipe is broken off close to a fitting and the pipe stem is so short that wrenches, pliers or other tools are inadequate for the removal of the stub. To remove such threaded 15 stubs the present extractor is inserted in the end of the stub and turned until its spiral threads engage the stub and cause it to turn, thereby unscrewing the stub from the fitting. This frequently avoids the necessity of removing a large 20 amount of piping in order to remove and replace the fitting when the stub could not be removed.

In cutting pipe a burr is formed at the cut ends of the pipe which very often is not removed. This 25 burr frequently interferes with the insertion of stub extractors, such as are shown in my aforementioned patent and it is necessary to ream out the burr before the extractor can be engaged with the stub. It is the principal object of the 30 present invention to provide such a stub extractor in which the inner end is formed so that it will ream out such a burr, if encountered, and permit the threads of the stub extractor to take hold.

35 It is another object of the present invention to provide such a stub extractor having threads of increased pitch so that they are sharper and will more quickly and positively engage the stub without danger of expanding the stub so as to 40 render its removal more difficult.

In the accompanying drawing:

Fig. 1 is a perspective view of a blank forging from which I manufacture my stub extractor.

Fig. 2 is a similar view showing the completed 45 stub extractor.

Fig. 3 is a side elevation of the completed stub extractor, shown in Fig. 2.

Fig. 4 is an end elevation of the blank shown in Fig. 1.

50 As illustrated in Fig. 1, the material from which my stub extractor is fashioned comprises a blank 10 which is preferably made of forged steel and includes a short shank element 11, a tapering intermediate section 12 and a tip 13. The shank 55 element 11 is preferably square in cross section

and the intermediate tapered portion 12 is four sided, terminating in corner edges which form continuations of the corners of the shank element 11. The tip 13 is also four sided and its corners form continuations of the corners of the intermediate section 12. In forging the blank the four faces of the intermediate section 10 are formed to provide rounding recesses 14 which extend from corner to corner, and the four side faces of the tip 13 are likewise formed to provide 10 rounding recesses 15 extending from corner to corner of the tip.

Having provided a blank as illustrated in Fig. 1 I place the blank in a furnace or oven and bring 15 it to a cherry red heat, whereupon the blank 15 is removed from the oven and the tip 13 thereof is inserted in a clamp or vise so that a rotative movement of the shank element 11 will twist the intermediate section, as indicated in Fig. 2, approximately three-quarters of a full turn, with 20 the result that the four sharp margins 16, 17, 18, and 19 of the intermediate section are formed into sharp threads, as indicated in Fig. 2.

The recesses 15 in the tip are preserved during 25 this twisting operation and therefore the tip 13, in the finished product, is provided with sharp corners 20, 21, 22, and 23 which are designed to act in the capacity of a reamer.

When my stub extractor has been properly 30 cooled following the twisting operations, the stub extractor is complete since no margin of the thread portions shown in Fig. 2 is necessary and no further grinding of the tip 13 is necessary to 35 sharpen its corners and provide a reamer. By indenting the blank during the forging operation it will be necessary that the threads are much sharper than if this were not done and it will also be seen that this recess, in the tip, provides the sharp corners so that the tip can be forced 40 into and ream out any burr in the stub. Since the degree of angle of the threads deviating from the axis of the completed extractor is decidedly obtuse, it will be found that my extractor will engage a broken pipe stub in a T or L pipe fitting 45 and will permit of uncrewing this stub from the fitting.

In imparting a reaming function to the tip 13 it will be seen that the corners of this tip can be ground into the form shown if the sides of the tip are not originally recessed, as shown in Fig. 1.

50 From the foregoing it will be apparent that the present invention provides a stub extractor in which the tip which is necessary for forming the extractor is utilized as a reamer for removing the burr on the inside of the stub, if it is necessary to 55

do so, and at the same time the threads of the extractor are also provided by the simple expedient of recessing the sides of the tip and the intermediate portion of the blank before it is twisted into its final shape.

5 I claim as my invention:

- 10 1. A device of the character described, comprising a one piece body which is angular in cross section throughout and includes a square shank, a coaxial tapered intermediate portion twisted to form spiral threads adapted to bite into and remove the stub from a pipe fitting and a coaxial tip of reduced size at the reduced end of said tapered intermediate portion, the corners 15 of said tip being arranged to describe a square and extending substantially parallel with the axis of the body and the faces of said tip between said corners curving inwardly toward the axis thereof thereby to form sharp edges of said corners which 20 act to ream out any burrs interfering with the insertion of said intermediate portion into the stub.

2. The method of forming a stub puller of the character described which comprises forging a blank of elongated form and generally square in cross section, the faces and corners of which are continuous from one end of said blank to the other, and having a shank, an intermediate portion of tapering form and a tip projecting outwardly from the small end of said intermediate portion, the four faces of said intermediate portion being recessed from corner to corner and substantially the full length thereof and the four side faces of said tip being likewise recessed from corner to corner to form four sharp edges extending parallel with the axis of the blank and twisting said shank relative to said tip to provide 15 sharp spiral threads on said intermediate portion, said sharp edges providing reaming edges to remove any burrs interfering with the insertion of said intermediate portion into a stub.
